ELECTRIC DISCHARGE DEVICE

Dietrich Günther Prinz, Wembley, Middlesex,
England, assignor to The General Electric
Company Limited, London, England, a company
of Great Britain

Application June 29, 1937, Serial No. 150,897
In Great Britain July 3, 1936

8 Claims. (Cl. 175—354)

This invention relates to means for operating electric discharge devices, such as mercury vapor devices, of the type having a cathode from which vapor is generated during operation, from an approximately sinusoidal A. C. supply, so that the arc, which has to be started in each cycle, can be started at a controlled point in the cycle.

It has been proposed to start an arc to the mercury cathode of a mercury arc device by application of high voltage to an inner auxiliary electrode. This involves, however, either inconveniently high voltages or frequencies or vapor pressure, or special arrangements, such as auxiliary hot cathodes.

15 It has been proposed also to start an arc by means of an external ignition electrode, for instance, a metal foil, fixed on the glass wall near the mercury surface. In this case, a cathode spot is very easily formed on the edge of the mercury probably due to the abnormally high electrical field arising at this sharp edge.

This method of ignition, however, has some considerable disadvantages.

Since the main anode circuit always contains 25 a certain self inductance, the anode current will increase, not suddenly, but at a finite rate. On the other hand, a minimum current of about 1 or 2 amps. is required for maintaining the cathode spot. Therefore, since the duration of the 30 spot is very short, the spot may be extinguished before a current sufficient to maintain it develops.

Another disadvantage of forming a cathode spot solely by means of an external electrode is 35 that, if the anode be placed far from the cathode (for instance, to protect it against evaporated or sputtered mercury), the main discharge may not be able to start from the cathode spot to the main anode, owing, for example to negative charges 40 formed on the glass walls or other insulators between cathode and anode.

The object of the present invention is to provide means for starting the discharge free from the disadvantages of either of these two methods.

45 According to the invention, means for the purpose specified comprise as part of the said electric discharge device, both an external electrode near the cathode and an internal auxiliary electrode, impulsive means for applying to the said external electrode an impulsive voltage, whereby a cathode spot is formed, and maintaining means for applying to the said internal auxiliary electrode a voltage of such magnitude, sign and duration that the cathode spot is maintained

by this voltage until the main discharge is established.

Certain embodiments of the invention will now be described, by way of example, with reference to the accompanying drawing. Of these, 5 Figures 1, 2 and 3 show, by way of example, various circuits for the production of the ignition peak voltage and for the supply of voltage to the auxiliary electrode. Figures 4 and 5 show, by way of example, some arrangements and 10 shapes of the auxiliary electrode.

In Figure 1, the discharge device consists of a glass envelope 1, containing a mercury pool 2 with a cathode lead 3, an anode 4 and an inner auxiliary electrode 5. This electrode 5 may consist of a simple wire, sealed through the glass wall, or of a ring (as shown), or it may be of any other suitable shape, of which examples are given in the modifications later described.

The external electrode 6 may consist of a wire 20 or other metal body, touching the glass near the mercury edge, but preferably of a metal foil fixed on the glass and surrounding the whole mercury pool.

Both the auxiliary electrode 5 and the external electrode 6 are connected with one terminal 25 of the high voltage winding of a transformer 7, the other terminal of the said high voltage winding being connected with the cathode lead 3. In the connection between the electrode 5 and the 30 said winding, there may be inserted a resistance 14, if desired.

The primary winding of the transformer 7 is connected with the A. C. source 8 through a resistance 9 and a grid glow tube 10, the grid of 35 which is connected with its cathode, through the secondary winding of a transformer 11 (which is preferably a peak transformer of the saturated iron core type) and a D. C. source 12.

The primary winding of the transformer 11 is fed by an A. C. source 13 of the same frequency as the A. C. source 8 and as the supply to the main circuit. This main circuit is shown in Figure 1 as an A. C. source a connected through a transformer b with the electrodes 3 40 and 4 of the discharge device 1 in series with a D. C. load c. The main circuit need not be as shown in Figure 1, but may be of any kind usual with vapour electric devices of the type specified.

The secondary voltage of the transformer 11, 50 in cooperation with the D. C. source 12, renders the grid glow tube 10 conductive, in known manner, at a definite moment of each cycle, so that an impulsive current then flows through the primary of the transformer 7. This impul- 55

sive current produces a high voltage on the secondary of the transformer 7, so that the external electrode 6 forms a cathode spot on the edge of the mercury pool. At the same moment, a discharge is started between this cathode spot and the inner auxiliary electrode 5; this discharge is maintained for a finite time by the magnetic energy stored in the transformer 7. If the transformer be suitably designed, this energy will be great enough to maintain the discharge to the electrode 5, until the main discharge to the anode 4 is established.

The A. C. sources 8 and 13, or the A. C. source 13 only, may be provided with phase shifting devices of known kind, so that the moment of ignition in each cycle may be varied in a manner well known in connection with all grid controlled converters and thus the mean current varied.

20 Figure 2 shows another example of a circuit according to the invention. Reference numerals 1'-8' have the same meaning as 1-8 in Figure 1. The peak voltages of the A. C. source 8' cause sparks to pass across the spark gap 9', thus charging the condenser 10' and causing a heavy current impulse to flow through the primary winding of the transformer 1'; a voltage peak therefore occurs in the secondary winding of this transformer and a cathode spot is formed by the external electrode 6 as described above.

It may be pointed out that two sparks occur in each cycle, thus producing one positive and one negative voltage peak on the external electrode 6'. Only the positive peak is used to form the spot. By inserting a second transformer in the circuit 1', 8', 9', 10', the second spark may be used for forming another positive voltage peak, so that another discharge device may be ignited alternately with the device 1'. This arrangement 40 may be useful in known symmetrical rectifier circuits, fed by 2-phase, 6-phase or 12-phase supplies. If the A. C. source 8' be provided with a phase shifting device, only one such device is required for each pair of rectifiers.

45 In Figure 2, a D. C. source 14' is connected through a resistance 15' with a condenser 16', this condenser in turn being connected with the auxiliary electrode 5' through an impedance 17'.

As soon as the cathode spot is formed by the 50 external electrode 6', a discharge takes place between the mercury cathode 2' and the auxiliary electrode 5', the duration of said discharge depending on the values of the condenser 16', the resistance 15', the impedance 17' and the voltage 55 of the D. C. source 14'. If these values be chosen suitably, the auxiliary discharge will be maintained until the main discharge has been established.

In the succeeding non-conductive part of the 60 cycle, the condenser 16' is recharged by the D. C. source 14' through the resistance 15'. This resistance must be high enough to prevent a continuous arc discharge taking place between the auxiliary electrode 5' and the cathode.

65 The impedance 17' need not be a pure ohmic resistance; it may be replaced by a self inductance; indeed it has been found that in this way a more uniform duration of the auxiliary discharge can be obtained.

70 In Figure 3, the reference numerals 1"-8" and 14"-17" have the same meaning as 1'-8' and 14'-17' in Figure 2; but the transformer 1" is a peak transformer of the saturated iron core type, producing an impulsive voltage. Its secondary winding may be connected directly be-

tween the external electrode 6" and the cathode 3"; its peak then must be made sharp enough and high enough to produce a cathode spot on the mercury. But preferably, as shown in the figure, the voltage on the external electrode 6" is made to rise still more sharply by inserting a spark gap 18 between the secondary winding of the transformer 1" and the electrode 6". The spark gap 18" may consist of a point separated from a plate by a distance such that only the 10 positive voltage peaks can break down the gap and reach the electrode 6". In this case, a resistance 19" may be provided to remove the electrical charges from the electrode 6" in the interval between the peaks.

15 The means for applying a voltage to the auxiliary electrode 5' which are shown in Figure 2 by the numerals 14"-17" may be used in the arrangement shown in Figure 1 in substitution for the connection of the electrode 5 through the resistance 14 with the secondary winding of transformer 7.

20 As mentioned above, it may be sufficient sometimes to form the auxiliary electrode as a simple wire sealed through the glass wall; in other cases, 25 it is preferable to give it a form that enables it to perform other functions as well.

25 In Figure 4, for example, the auxiliary electrode is formed as a baffle or screen protecting the anode from the vapour stream and the sputtering from the cathode spot. In this figure, the glass envelope 21 contains an anode 22, sealed and supported at 23, and an auxiliary electrode 24, sealed into and supported by a foot-tube and pinch 25. The annular depression formed by 30 sealing the foot-tube to the glass envelope is filled with mercury 26, for which a leading-in wire 27 is provided. The annular form of the mercury pool has the advantage of increasing the length of the mercury edge for a given amount of mercury; a metal foil forming the external electrode can be applied not only on the outer side 28, but also on the inner side 29 of this mercury pool. Furthermore, its presence on this inner side makes it easy to cool the mercury (for example 40 by a blast of air); cooling is known to promote the formation of cathode spots.

45 The diameter of the auxiliary electrode 24 is greater than that of the anode 22 and that of the mercury pool 26, so that the anode is protected 50 from the vapour stream produced by the cathode spot as well as from any sputtered mercury.

55 In Figure 5, another shape of the auxiliary electrode is shown. In this figure, the glass vessel 30 contains in a side arm 31 an anode 32 supported by a rod 33 sealed in at 34, the said rod being protected by a quartz sheath 35 held in position by washers 36 and a spring 37. 38 is the mercury pool, and 39 is the cathode lead. The auxiliary electrode 40, supported on a lead 60 sealed in at 42, is formed as a grid surrounding the anode 32. This arrangement facilitates the starting of the discharge between the cathode and anode; and, if the discharge tube be used as a rectifier, it also decreases the risk of back firing 65 during the inverse half cycle. When using a circuit according to Figure 1 or 2, the potential of the auxiliary electrode never differs very greatly from that of the cathode during the inverse period; the electric field tending to produce a 70 reverse discharge is confined to the space between the anode and auxiliary electrode. On the other hand, a back discharge between the anode and the auxiliary electrode is improbable because these electrodes are near together and, in the cir- 75

cuit according to Figure 1, because of the resistance of the transformer windings and the additional resistance 14 inserted in the lead to the auxiliary electrode 5.

5 I claim:—

1. In a mercury vapor discharge device, a tube having an anode and a cathode, the cathode comprising a pool of mercury from which vapor is generated during operation, a main circuit carrying alternating current of known frequency connected for discharge between the anode and cathode of said tube, said main circuit including a direct current load, an external electrode arranged to cooperate with the mercury pool of the cathode in the formation thereon of a cathode spot, a circuit between said external electrode and the cathode carrying an impulse current for establishing a positive potential on the external electrode during each cycle of the alternating current in the main circuit for forming the cathode spot on the mercury pool, an auxiliary electrode mounted within the tube between the anode and cathode for cooperation with the cathode spot, and circuit means arranged to provide an impulse current for discharge between said auxiliary electrode and the cathode spot for maintaining the cathode spot until the main circuit discharge is established.
2. The mercury vapor discharge device as in claim 1 wherein the current for providing the impulse discharge between the auxiliary electrode and the cathode spot is derived from the circuit which is arranged to form said cathode spot on the mercury pool.
3. The mercury vapor discharge device as in claim 1 wherein the impulse current for forming the cathode spot on the mercury pool is provided by the secondary of a transformer the primary of which is supplied with unidirectional impulse current produced by passing an alternating current of proper frequency through a glow tube rectifier.
4. The mercury vapor discharge device as in claim 1 wherein the impulse current for forming the cathode spot on the mercury pool is pro-

vided by a transformer the secondary of which is arranged to supply a unidirectional impulse current derived from an alternating current of proper frequency and the impulse current for the discharge between the auxiliary electrode and the cathode spot is provided by a branch circuit from the secondary of said transformer.

5 The mercury vapor discharge device as in claim 1 wherein the impulse current for forming the cathode spot on the mercury pool is provided by the secondary of a saturated core transformer the primary of which is supplied with impulse current of proper frequency from an alternating current source with a condenser and spark discharge in circuit.

10 15 6. The mercury vapor discharge device as in claim 1 wherein the impulse current for forming the cathode spot on the mercury pool is provided by the secondary circuit of a saturated core transformer which circuit includes a unidirectional spark discharge, the primary of the transformer being supplied from an alternating current of proper frequency.

20 25 7. The mercury vapor discharge device as in claim 1 wherein the impulse current for the discharge between the auxiliary electrode and the cathode spot is provided by a condenser arranged to be charged from a direct current source and to be discharged between the auxiliary electrode and the cathode spot with the formation of the 30 cathode spot.

25 30 35 40 8. The mercury vapor discharge device as in claim 1 wherein the impulse current for forming the cathode spot on the mercury pool is provided by a transformer the secondary of which is arranged to supply a unidirectional impulse current produced from an alternating current of proper frequency and the impulse current for the discharge between the auxiliary electrode and the cathode spot is provided by a condenser arranged to be charged from a direct current source and to be discharged between the auxiliary electrode and the cathode spot with the formation of the 45 cathode spot.
